United States Patent Office

Des. 177,448
Patented Apr. 10, 1956

177,448

BEVERAGE TRAY

William W. Welch, Sr., William E. Clements, and James F. Mariol, Cincinnati, Ohio; said Clements and Mariol assignors to said Welch

Application August 29, 1955, Serial No. 37,701

Term of patent 14 years

(Cl. D44—10)

We claim:

The ornamental design for a beverage tray, as shown.
